CORE GRINDER

John A. Rosmait, Appleton, Wis., assignor to D. J. Murray Manufacturing Co., Wausau, Wis., a corporation of Wisconsin

Application February 17, 1945, Serial No. 578,440

2 Claims. (Cl. 51—124)

1

This invention relates generally to the art of grinding, and relates more specifically to improvements in the construction and operation of machines for facilitating the dressing and grinding of foundry cores or the like.

The primary object of my present invention is to provide a new and useful foundry core grinder which is simple in construction, flexible in its adaptations, and highly efficient in operation.

When manufacturing sand cores for foundry use, it frequently becomes desirable to construct the cores in the form of mating sections which are subsequently pasted or glued together to produce the completed cores. In order to produce perfect final core assemblages, the sections of each core must be dressed or ground so as to provide accurate plane and smooth surface coaction along the pasted areas, and to also obviate broken bounding edges at these coacting surfaces. This grinding operation has heretofore been rather slow and tedious, especially when producing large quantities of similar sectional cores; and in many cases large quantities of core sections either had to be scrapped, or the cost of production was materially increased due to subsequent patching necessitated by broken edges or the like. The prior methods of manufacturing sectional sand cores have therefore proven quite unsatisfactory and costly for various reasons, and it has heretofore been impossible to rapidly produce perfect composite cores having neat and highly finished appearance, at moderate cost.

It is therefore a more specific object of the present invention to provide an improved core grinding machine which may be utilized to overcome all of the above mentioned difficulties, and which is adapted to quickly and effectively produce smooth and perfectly flat surfaces of coaction upon the core sections, without breaking or marring the bounding edges of these surfaces.

Another specific object of this invention is to provide an improved core grinding assemblage of relatively compact and durable construction, which may be disposed in any convenient location, and safely operated by a novice to produce excellent results.

A further specific object of my invention is to provide an improved core grinding mechanism having large capacity, and adapted to be readily manipulated and adjusted to dress sand cores or the like, having diverse sizes and shapes.

Still another specific object of the invention is to provide a precision core grinder having enormous capacity, and which is operable without

2

danger of chattering to produce perfectly smooth and clean surfaces of coaction, thereby effecting great savings in paste and labor necessary for production of the final cores.

5 An additional specific object of this invention is to provide an efficient core dressing mechanism which may be constructed and operated at moderate cost, and in which all parts are readily accessible for inspection while being thoroughly protected against sand and grit during normal use of the equipment.

These and other specific objects and advantages accruing from the invention, will be more clearly apparent from the following detailed description.

15 A clear conception of the various features constituting my present improvement, and of the mode of constructing and of utilizing core grinders embodying the invention, may be had by referring to the drawings accompanying and forming a part of this specification wherein like reference characters designate the same or similar parts in the different views.

20 Fig. 1 is a part sectional side elevation of a relatively small and portable core grinder built according to the invention, portions of the assemblage having been broken away to more clearly reveal normally concealed parts;

25 Fig. 2 is a top view of the upper portion of the core grinding unit of Fig. 1;

30 Fig. 3 is a part sectional side elevation of another core grinder embodying the invention but of larger capacity than that of Fig. 1, this modified machine also having portions broken away in order to reveal normally concealed structure, and showing the core support revolvable from a slow speed motor directly through an endless belt drive;

35 Fig. 4 is an enlarged central vertical section 40 through the anti-friction bearing for mounting the core support upon the main column of the machine;

45 Fig. 5 is a transverse horizontal section through the machine of Fig. 1, taken along the line 5—5 and viewed in the direction of the arrows;

50 Fig. 6 is an enlarged central vertical section through the anti-friction journal and thrust bearing for the grinding wheel supporting shaft; and

55 Fig. 7 is a transverse horizontal section through a large capacity machine such as shown in Fig. 3, the section being taken generally along the line 7—7 but above the annular apron associated with the revolvable core support, and the core support being rotatable by an electric motor

through speed reducing mechanism in addition to a belt drive.

While the invention has been shown and described herein as being especially applicable to foundry core grinders the grinding wheels of which are driven by electric motors, it is not my desire or intent to unnecessarily restrict the scope or utility thereof by virtue of this limited disclosure.

Referring to the drawings, and especially to Figs. 1, 2, 4, 5 and 6, the relatively compact portable core grinder shown therein comprises in general a lower base 9 mounted on three wheels 10, and having a sturdy upright column 11 firmly attached thereto at the lower extremity of the column; an upper bracket 12 vertically slidably embracing the upper cylindrical portion of the column 11 and coacting with a spline 13 to positively prevent rotation of the bracket about the column axis; a grinding wheel 14 secured to the lower extremity of a vertical shaft 15 disposed parallel to but remote from the column axis, and having its medial portion journalled for rotation in an anti-friction bearing assemblage 16 carried by the bracket 12, while its upper end is provided with a pulley 17; a driving motor 18 mounted upon the bracket 12 near the column 11 and being drivingly connected to the pulley 17 by a driving belt 19; a cap 20 resting upon the upper end of the column 11 and having an adjusting spindle 21 journalled for rotation therein, the upper end of the spindle being provided with a hand wheel 22 for effecting rotation thereof while the lower elongated spindle portion 23 is screw threaded for coaction with internal screw threads formed on the bracket 12; and a core supporting member 24 having a hub 25 rotatable about the lower part of the upper cylindrical portion of the column 11 and coacting with an annular shoulder 26 formed on the medial portion of this column through an anti-friction thrust bearing assemblage 27, the member 24 also being provided with an integral supporting plate or portion 28 for supporting sand cores 29 or the like, and which is swingable horizontally beneath the grinding wheel 14.

The main base 9 is preferably constructed in a durable manner and in the form of a three armed spider so that two of the transporting rollers 10 are disposed some distance away from and on opposite sides of the column 11, while the third roller 10 is located forwardly of and beyond the axis of the shaft 15 and plate 23, as shown in Fig. 5. The base 9 thus provides a substantial and firm portable support for the entire core grinder; and in order to facilitate transportation of the machine from place to place, the base 9 may also be provided with a draft handle 30 adapted to be held in upright position by means of a hook 31 secured to the column 11, when the handle is not in use, as shown in Figs. 1 and 5. The lower end of the upright column 11 should be firmly secured to the base 9 in any suitable manner, and the column is preferably formed hollow as shown, and has the elongated spline 13 and shoulder 26 rigidly and permanently associated therewith. The entire portion of the column 11 above the fixed shoulder 26 is cylindrical and should be formed for snug but sliding coaction with the bore of the bracket 12, so that this bracket may be adjusted vertically along the column 11 but will be prevented from revolving about the column axis by the spline 13.

The rotary grinding wheel 14 is detachably secured to and suspended from the lower end of the shaft 15 by means of a nut 32, and may be provided with a suitable guard 33 as indicated in Figs. 1 and 2; and the combined guide and thrust bearing assemblage 16 which is carried by the forward portion of the bracket 12 and in which the shaft 15 is journalled, should be so constructed that the shaft 15 cannot tilt or shift longitudinally of its axis. This anti-friction bearing assemblage is illustrated in detail in Fig. 6, and comprises vertically spaced upper and lower ball bearings 34, 35 respectively, of which the upper bearing 34 should be located as near as possible to the pulley 17 while the lower bearing 35 is likewise disposed as near as possible to the grinding wheel 14. The upper anti-friction bearing 34 is moreover formed and held in place by a retaining plate so as to assume upward thrust, while the lower anti-friction bearing is formed and likewise held in place so as to assume downward thrust imposed upon the shaft 15, thereby insuring accurate rotation of the lower grinding face of the wheel 14 in any desired horizontal plane as predetermined by adjustment of the bracket 12 along the column 11. The shaft 15 and grinding wheel 14 are rotatable at relatively high speed, by power applied to the pulley 17 from the motor 18 through one or more endless V-belts 19, and the tension of these belts may be adjusted by shifting the motor 18 upon its carrying bracket 12 with the aid of tensioning screws 36 shown in Fig. 2.

The adjusting spindle supporting cap 20 rests upon the upper end of the column 11 and may be firmly secured thereto in any suitable manner, and the manipulating hand wheel 22 which is secured to the upper extremity of the spindle 21 may be provided with a number of grip handles 37 as depicted in Figs. 1 and 2. The threaded spindle portion 23 and the spline 13 should preferably be of considerable length, and since the spindle 21 is journalled for free rotation in the fixed cap 20 but is prevented from shifting axially relative to this cap, rotation of the spindle with the aid of the hand wheel 22 will obviously cause the bracket 12 to move up or down dependent upon the direction of said rotation and by virtue of the screw thread coaction of the spindle portion 23 with the internal bracket threads. This adjustment of the bracket 12 along the column 11 permits the grinding wheel 14 to be positioned at any desired height above the core supporting plate 28; and the bracket 12 may be locked or clamped to the column 11 in various positions of adjustment, by means of a locking screw element 38 coacting with lugs 39 formed on the lower split portion of the main hub of the bracket 12, as clearly shown in Figs. 1 and 2. The wheel driving belt 19 may also be normally concealed by a guard 40 as shown diagrammatically in Figs. 1 and 2, and above which the hand wheel 22 is located, but this guard should be readily removable and is not essential, although it does protect the operator while manipulating the hand wheel.

Although the bracket 12 and grinding wheel 14 may be thus adjusted vertically along the main column 11, the core supporting assemblage 24 is not shiftable along this column, but is merely swingable about the column axis as a center. As previously indicated, the core supporting structure comprises a hub 25 snugly embracing but swingable about the upper cylindrical portion of the column 11, a core support

ing plate 28 formed integral with the hub 25, and a thrust bearing assemblage interposed between the lower end of the hub 25 and the annular fixed shoulder 26 formed on the column 11. As shown in Figs. 1 and 4, the hub 25 is preferably of considerable vertical length and bears against the column 11 at vertically spaced zones, being provided with a lubricant injection fitting 41 for introducing abundant grease to the space between the bearing zones. The upper end of the hub 25 is closed and concealed by an annular cap 42 secured to the column 11, and the anti-friction thrust bearing assemblage 27 consists of an annular ball bearing 43 which is thoroughly concealed and protected by a collar 44 secured to the bottom of the hub 25. This vertically elongated bearing assemblage 27 while permitting the supporting plate 28 to be swung freely about the column 11 in a horizontal plane, positively prevents the core support from moving out of this fixed plane.

The core supporting plate 28 of the relatively small core grinder of Figs. 1 and 5, and which is swingable back and forth about the central column axis, may be circular or of any other desired shape, and is provided with a series of anchoring grooves 45 of well known construction to which the mounting frame 46 of the cores 29 may be firmly secured by means of bolts 47 or the like. The table or plate 28 may also be provided with suitable gripping handles 48 for facilitating swinging thereof, and it is to be noted that the centerline of the plate 28 is swingable about the central axis of the column 11 on a radius which is approximately equal to the distance from the column axis to the center of the grinding wheel supporting and driving shaft.

The somewhat modified larger capacity core grinders shown in Figs. 3 and 7, are quite similar to the smaller machine which has just been described in detail, and function the same as the smaller grinder except that the cores 29 may be automatically swung about the column axis by power applied to the core support. Since the column 11, bracket 12, grinding wheel 14 and the supporting, adjusting and driving elements associated with these various parts are the same in structure and function in both machines, their description will not be repeated. In the large capacity machine, the lower extremity of the main column is rigidly secured to a relatively heavy and sturdy base plate or base 49 of considerable area, and the core supporting assemblage 59 comprises an annular table or horizontal plate 51 formed integral with a pivot hub 25 and adapted to be constantly rotated about the column axis by means of a motor driven tapered friction roller 52 coating with an annular lower surface 53 formed on the table plate 51. The top of the plate 51 may be provided with a series of radial core anchoring recesses or T-grooves 45 formed in radial stiffening ribs 54, so that an annular series of cores 29 may be mounted upon the revolvable table, and the periphery of the plate 51 is provided with an annular apron 55 extending downwardly below the driving roller 52. This driving roller 52 is mounted upon a shaft 56 journaled in a bracket 57 secured to the base 49, and the inner end of the shaft 56 carries a pulley 58 which may either be driven directly from a slow speed motor 59 through speed reducing endless belts 60, as shown in Fig. 3; or from a high speed motor 61 through speed reduction gearing 62 and belts 60, as illustrated in Fig. 7. In either case, the revolution of the

core supporting plate 51 by power, should be at relatively slow speed in order to grind a perfectly smooth surface in one pass of the relatively soft sand core 29 beneath the abrasive wheel 14.

Since the operation and functioning of the two machines is substantially the same, it will suffice to describe the mode of use of only one of the core grinders, so that the mode of utilizing the smaller core grinder will be specifically described. During normal use of the core grinding machine disclosed in Figs. 1, 2 and 5, the core 29 which is to be dressed should first be firmly applied to its frame 46 and this frame should be firmly attached to the core supporting plate 28 with the aid of bolts 45. The plate 28 with the core 29 attached thereto will then be freely swingable about the central vertical axis of the column 11 in an obvious manner. The grinding wheel 14 should then be vertically adjusted by releasing the clamping screw 38 and manipulating the hand wheel 32 so that the lower plane face of the wheel 14 will be at the proper distance from the upper plane face of the plate 28, in order to properly dress the upper surface of the core 29 when the core is swung into the zone of action of the wheel, and the clamping screw 38 should thereafter be manipulated so as to lock the bracket 12 in the properly adjusted position. The motor 18 may then be placed in operation to cause the grinding wheel 14 to revolve rapidly about the central axis of its supporting and driving shaft 15, after which the core supporting plate 28 may be swung about the central axis of the column 11 so as to cause the core 29 to pass beneath the revolving grinding wheel.

Because of the fact that the sand cores 29 are relatively soft as compared to the grinding wheel 14, it is only necessary to cause the wheel to travel once over the core, in order to insure the production of smooth core faces, but the wheel should be moved slowly in order to avoid breakage of the core edges adjoining the ground surfaces. In this manner, the successive cores may be rapidly and effectively dressed and subsequently united along the smooth and plane dressed surfaces, with the aid of paste or other adhesive in a well known manner, and by properly manipulating the supporting plate 28, chipping and breakage at the edges of the dressed surfaces may be entirely eliminated, thus avoiding necessity of subsequent patching.

As previously indicated, the normal operation of the modified core grinding machine shown in Figs. 3 and 7 is the same as that of the machine shown in Figs. 1, 2 and 5, but with the larger machine a continuous annular series of cores 29 may be dressed automatically by utilizing a motor for driving the annular core supporting table plate 51. A series of similar cores 29 may obviously be secured to the plate 51, and this plate may subsequently be revolved about the central axis of the column 11 by applying power to the friction roller 52, and as each of the successive cores 29 is passed beneath the revolving wheel 14 which has previously been vertically adjusted to the proper height, the upper surfaces of the successive cores 29 will be neatly dressed and provided with smooth and perfectly plane surfaces. Obviously the capacity of the larger machine may be made considerably greater than that of the smaller portable machine, but in both cases the result will be effective dressing of the cores so that they can be subsequently united along the dressed surfaces without difficulty.

From the foregoing detailed description it will be apparent that my present invention provides an improved core grinder which besides being extremely simple, compact and durable in construction, is also highly efficient in use. The elongated anti-friction bearings provided for the grinding wheel driving shaft 15 and for the core supporting table or plate, will prevent misalignment of the wheel and table relative to each other and will thus insure the provision of perfectly smooth and plane surfaces. The adjustment afforded for the bracket 12 and grinding wheel 14 obviously provides extreme flexibility in utilizing the machine to dress cores of different sizes and shapes, and the smaller machine while being of lesser capacity than the larger machine, is extremely compact and portable so that it can readily be moved into various localities. In both machines the grinding wheel 14 while being vertically adjustable, is effectively held against possible displacement relative to the central axis of the main column 11, and in both machines the core supporting table or plate is likewise effectively prevented from becoming misaligned with respect to the column axis while being freely swingable about this axis. While the anti-friction bearings 34, 35, 43 have been shown as ball bearings, it is to be understood that roller or other types of anti-friction bearings may be employed in place of these ball bearings, in a manner well known in the art. The improved machine may obviously be built and operated at moderate cost considering its effectiveness, and the invention has proven highly successful and advantageous in actual commercial use.

It should be understood that it is not desired to limit this invention to the exact details of construction or to the precise mode of use, herein shown and described, for various modifications within the scope of the appended claims may occur to persons skilled in the art.

I claim:

1. A core grinder comprising, a base, an upright column mounted upon said base and having an annular outwardly projecting shoulder and a cylindrical portion projecting upwardly from said shoulder, a core support swingable about said cylindrical column portion and coacting with the upper surface of said shoulder to prevent movement of the support along the column, a bracket having a hub slidably cooperable with said cylindrical column portion and being provided with an upright bearing remote from said hub and directly above the core carrying portion of said support, an abrasive wheel journaled for rotation

55

in said bearing and having a grinding face revolvable beneath said bearing parallel to the plane of swinging of said core support, a motor mounted directly upon said bracket hub, a rotary motion transmitting drive connecting said motor and said wheel above said bearing and said bracket, a spline interposed between said hub and said cylindrical column portion for positively preventing swinging of said bracket about said column, a cap fixedly secured to the upper extremity of said column, a manually operable screw threaded adjusting spindle journaled in said cap and having its lower end cooperable with said bracket to move the same along said column while its upper actuating end is disposed above said drive, and means for locking said bracket to said column to prevent displacement of the bracket by said spindle.

2. A core grinder comprising, a base, an upright column mounted upon said base and having an annular outwardly projecting shoulder and a cylindrical portion projecting upwardly from said shoulder, a core support swingable about said cylindrical column portion and coacting with the upper surface of said shoulder to prevent movement of the support along the column, a motor also mounted upon said base beneath said support, a friction drive interposed between said motor and said support for imparting swinging motion to the latter, a bracket having a hub slidably cooperable with said cylindrical column portion and being provided with an upright bearing remote from said hub and directly above the core carrying portion of said support, an abrasive wheel journaled for rotation in said bearing and having a grinding face revolvable beneath said bearing parallel to the plane of swinging of said core support, another motor mounted directly upon said bracket hub, a rotary motion transmitting drive connecting said last mentioned motor and said wheel above said bearing and said bracket, a spline interposed between said hub and said cylindrical column portion for positively preventing swinging of said bracket about said column, a cap fixedly secured to the upper extremity of said column, a manually operable screw threaded adjusting spindle journaled in said cap and having its lower end cooperable with said bracket to move the same along said column while its upper actuating end is disposed above said drive, and means for locking said bracket to said column to prevent displacement of the bracket by said spindle.

JOHN A. ROSMAIT.
